METHOD FOR RECEIVING AND TRANSMITTING SIGNALS

Franz Klement, Hohenneudorf, near Berlin, Germany, assignor to Siemens & Halske, Aktiengesellschaft, Siemensstadt, near Berlin, Germany, a corporation of Germany

Application July 16, 1937, Serial No. 154,060
In Germany July 16, 1936

19 Claims. (Cl. 178—39)

My invention relates to an arrangement for receiving and transmitting signals, for instance, telegraph impulse combinations by means of air, gas or liquids.

- 5 Telegraph receiving apparatus are known in which the electric impulses transmitted over the long-distance circuit are converted into compressed air impulses and supplied to a selecting mechanism by means of a rotary air distributor.
- 10 In this case the compressed air impulses produced by the receiving relay, control the selecting devices in accordance with the received impulse combinations. The known arrangements of the above-indicated character have, however,
- 15 15 the disadvantage in that they require complicated translating devices which are very difficult to manufacture.

According to the present invention an arrangement for transmitting signals by compressed air and/or suction air is employed in which the air impulses produced in a known manner by the receiving relay and transmitted to a distributor are utilized in the manner that a sum or a difference is formed of the impulses or of magnitudes 25 (path, pressure, quantity) allotted to the same. The device may be operated instead of with air also with any other gas or with a liquid medium; for instance, oil without departing from the spirit of the invention.

30 The use of mechanical translators in connection with the telegraph apparatus is well known in which the impulses are utilized by forming sums or differences. However, such arrangements operate in the manner that a plurality of 35 discs or gears are displaced with respect to one another. In the case of great line speeds required in modern telegraphy great difficulties arise in such mechanical translators owing to the considerable friction and mass of the numerous moved parts and owing to the numerous inexact engagements. These drawbacks are removed according to the invention insofar as a piston actuated by air or the like may be considerably accelerated, even at low pressures. Within 40 reasonable limits the stroke of the piston may be chosen at will and finally a movement may be effected in both directions by the use of suction air or compressed air for "current" and "no-current" impulses or for positive and negative impulses. The sums or the differences of some or of 45 all impulses of a telegraph impulse combination may also be formed by the displacement of rotary pistons which may be arranged to rotate in a cylinder.

50 In order to attain an exact mid-point scan-

ning the impulses of the gaseous or liquid medium act according to the invention on the selecting and adjusting devices only in their mid-point.

In the simplest case the mid-point scanning 5 may be attained by correspondingly designing the air distributor or the slide valve. To this end, the air channels in the distributor are made as narrow as possible. In this case, the air acts on the selecting and adjusting devices only during 10 a short time which corresponds to the mid-point of the electric impulse. In order to supply the necessary amount of air to the last-mentioned devices also a considerably higher air pressure is, therefore, necessary in carrying out the method 15 under consideration.

According to the invention the control member common to all impulses and controlled by the receiving magnet is employed for the mid-point scanning. It is very essential that the movement 20 be caused by compressed or suction air, even if no mid-point scanning is performed. It is of great advantage, if the receiving magnet of the telegraph apparatus is relieved in the manner that for every impulse the armature engages once 25 the magnet.

According to the invention particular control distributors mounted on a shaft preferably together with the operating distributor for the adjusting device and driven in common are 30 employed in connection with the control.

Further, it has been found that it is advantageous to effect the control with the aid of valves, since in this manner the moved masses 35 of the control member become very small.

Further details of my invention will be apparent from the following description taken in connection with the accompanying drawings in which

Figs. 1 shows an embodiment of the invention 40 in which the impulses coming from the distributor are transmitted to a slide piston arrangement.

Figs. 2 and 3 show another form of the invention 45 in which a rotation is effected which is preferably transmitted to a type wheel.

Fig. 4 shows a view of a rotary piston and Fig. 5 shows a sectional view thereof.

In Fig. 6 is schematically shown the manner 50 in which a distributor with a rotary piston according to the invention may cooperate with a translator having a slide piston as shown in Fig. 1, and

Figs. 7 and 9 show another form of the inven- 55

tion in which the control of the distributors is effected by a valve.

In Fig. 1, A designates a cylinder in which are arranged five pistons 1 to 5. The pistons are slidably coupled with one another and with the cylinder by means of rods 16, as shown in the sectioned portion of piston 4. These rods are of varying lengths to limit the movement of the pistons with respect to one another so that the piston 1 may be displaced by one spacing unit with respect to the cylinder, the piston 2 by two units with respect to piston 1, the piston 3 by four units with respect to piston 2, the piston 4 by eight units with respect to piston 3, and the piston 5 by sixteen units with respect to piston 4. The pistons are shifted apart with respect to one another by introducing compressed air into the intermediate spaces, whereas the pistons may be caused to approach one another by withdrawing with the aid of a vacuum the compressed air from said intermediate spaces. In other words, the pistons may be moved in one or the other direction by applying positive or negative fluid pressure. This may be also attained by a compression spring F. Preferably suction air and a compression spring are utilized in accelerating the adjustment. The movement of the piston 5 is transmitted to a type wheel B or any other recording device, for instance, 30 through a rack Z.

In each position of the pistons the corresponding intermediate spaces must communicate with the respective air conduits. The latter enter, therefore, the ports 9 which have a corresponding length in axial direction. This may also be effected in another manner; for instance, by providing, as shown, bevelled portions at the ends of the pistons, which also may cooperate with the extended ports.

40 The arrangement operates as follows: The receiving magnet M at rest, i. e. in normal condition, is traversed by a current and thus firmly holds the armature 6. The three-armed ratchet lever 8 pivotally mounted as indicated at 7 is connected with armature 6 and arrests with its arm 8' by means of the locking nose 9 cam disc C fixed on the receiver shaft 10 which latter is driven through a sliding coupling (not shown) so that it will rotate whenever released by arm 8'. On the receiver shaft 10 are further fixed the rotor D' of the distributor valve D and the printing cam disc E. The starting impulse deenergizes magnet M and causes the armature to fall away, thus releasing the receiver shaft 10 which begins to 50 rotate in clockwise direction. After each $\frac{1}{4}$ rotation the armature 6 is momentarily pressed against the magnet by means of the cams 11 which engage arm 8'' and rock it counterclockwise so that thereby the armature 6 is firmly held or released by the magnet M after the passage of a cam, depending upon whether or not a current impulse is present at that moment. To the armature 6 is, furthermore, connected the slide valve 1. The latter connects the port 12 of the valve 60 rotor D' with the compressed air conduit G when the armature is attracted or with the vacuum conduit J when the armature is released. The ports 13 in the stationary part of the distributor D are of such peripheral widths that they register 65 70 with the port 12 only during a fractional portion of the impulse. In this manner the impulses are scanned as regards time in the mid-point of the time period so that a correction or the proper translation even of distorted impulses is attained. The conduits 14 leading to the translator

are connected to the ports 13. After the five impulses are scanned the cam E presses the pressure hammer K against the type wheel. The cam 15 of the cam disc C presses the armature 6 against the magnet. This cam has a larger peripheral extent than the cams 11 and it thus firmly holds the armature for a longer time against the magnet upon the arrival of a locking impulse. This cam 15 is so positioned that during its operation locking nose 9 engages arm 8' of the ratchet lever 8 so that the receiver shaft comes to rest.

5 While Fig. 1 shows an embodiment of the invention in which slide pistons are employed for operating the type drum, Figs. 2 and 3 employ radial vanes or blades for that purpose.

In Figs. 2 and 3 is shown a cylinder 101 closed by end plates not shown. Five sector-shaped blades (rotary pistons 103 to 107) are arranged within this cylinder and are capable of being 20 rotated about a stationary shaft 102. Each of these rotary pistons, of which 105 is shown in detail in Figs. 4 and 5, is mounted on a ring 103' to 107' respectively. The rotary pistons may, therefore, be rotatably moved on shaft 102 independently of one another. The movement of the blades 103 to 107 with respect to one another and that with respect to the front end plate of the cylinder are limited by an arcuate groove 108 in which engages a pin not shown which is 30 arranged in the adjacent blade or in the case of the rotary piston 103 in the front end plate of the cylinder. Besides the rotary pistons also a further blade 109 is arranged within the cylinder having the same form as the rotary pistons and 35 being firmly secured to the cylinder wall 101. The lower end of the blade 109 extends closely to the rings 103' to 107'. The grooves 108 are so dimensioned that the rotary piston 103 may be moved with respect to the blade 109 by one arc unit, the piston 104 with respect to 103 by two units, the piston 105 with respect to 104 by four units, the piston 106 with respect to 105 by eight units and the piston 107 with respect to 106 by sixteen units. The ring 107 allotted to the piston 107 is 40 axially extended and passes through the front end plate of the cylinder. The part to be adjusted by the impulse combination—in the case of the type printing telegraphs the type wheel—is secured to the ring 107'. When spacing the type 45 wheel it is to be considered that the piston 107 does not describe a complete circle but only an arc whose magnitude amounts to $360^\circ - 6\alpha$ where α is the angle taken up by a piston.

In the case of the five-unit code the compressed air and suction air is supplied through five longitudinal ducts 103'' to 107'' arranged in the shaft 101, each of the ducts extending to an opening 110 in one of the five blades.

55 As will be seen from Figs. 4 and 5 the ducts end first in a groove 111 of the shaft 102, whence the air passes through a bore 112 into the above-mentioned outlet opening 110. The space between the rotary piston 107 and the stationary blade 109 is brought in the present case under normal pressure by an opening 113, i. e., it communicates with the outside atmosphere.

60 Similarly to the manner shown in Fig. 1, the individual rotary pistons receive the impulses of the gaseous or liquid medium from a receiving magnet system through a revolving distributor and assume corresponding positions. As in the case of Fig. 1 sums or differences from which results a corresponding position of the type wheel 70 are formed of the relative movements of the in- 75

dividual rotary systems. Instead of the revolving distributors slide pistons may also be employed for the control.

Fig. 6 shows an arrangement which serves to control a multi-row type wheel 114. For the control of this type wheel all together 114 rotary and sliding movements are necessary. In this case the control of the longitudinal displacement of the type wheel is effected by a single impulse of an impulse combination, whereas the rotary motion is controlled by the other portion of the impulse combination. The longitudinal displacement is preferably brought about in a slide piston system 115 of the type shown at A in Fig. 1, whereas the type wheel is rotated by a rotary piston system 116 which is designed substantially as shown in Figs. 2 to 5. The slide piston system of the cylinder 115 is provided with a connecting shaft 117 which passes through the hollow shaft of the rotary piston system 116. The end ring 119 of the end piston projects from the cylinder 116 of the rotary piston system. To the end ring 119 are secured two driving pins 118 along which the type wheel 113 may be shifted. These driving pins 118 control, therefore, the rotation of the type wheel 114.

The transmission of the 32 combinations of the five-unit code requires, therefore, five pistons; for instance, two rotary pistons and three slide pistons. For the letter-figure-shift preferably a further piston is arranged which moves the type wheel into the position corresponding to the desired type group. This piston may be either of the rotary or of the sliding type. The distribution of the 32 characters of each type group over four rings of the type wheel results, therefore, in an eight-row type drum which is adjusted to four rings each in the case of a letter-figure-shift. Also a six-unit code may be employed and the type group changeover may be brought about by the sixth impulse.

In this form of the invention two translating devices are, therefore, provided as mentioned in the introduction. If the arrangement operates in such a manner that a sliding motion of the type wheel is brought about, for instance by the first and last impulse, and a rotary motion by the other impulses, for instance by the second to the fourth impulse, the piston corresponding to the first impulse has time to reach its end position until the third impulse is utilized. On the other hand, also the pistons corresponding to the second to fourth impulse need only attain their end position at the end of the fifth impulse in order to effect a proper print of the chosen character.

Figs. 7 and 8 show the control of a piston arrangement by means of a valve which is controlled by the receiving magnet.

In the operating cylinder 201 are arranged five pistons, for instance in the manner shown in Fig. 1, which adjust through a rack bar rod 202 and a gear 203 a type wheel 204 in accordance with the air impulses conveyed from the distributor 210 through the ducts 205 to 209. The adjustment of the type wheel is thus effected in the same manner as shown in Fig. 1.

Positive or negative air pressure is supplied according to the signs + or - with the aid of the control port 211 in piston valve 214 from the conduits 212 and 213 to the distributor 210 by a pressure generator not shown. The movement of the piston valve 214 designed in the form of a slide valve depends on the one hand upon the state of excitation of the receiving magnet 215

whose armature 216 is firmly connected to the piston 214 through the rod 217. The piston 214 communicates with two control distributors 221 and 222 through the conduits 218, 219 and 220, the distributor 222 being continuously under the influence of suction air or negative pressure and the distributor 221 being continuously supplied with compressed air. To simplify the construction of the arrangement both control distributors 221 and 222 and the working distributor 210 are mounted on the same shaft as indicated by the dash and dot line.

It is assumed that the apparatus operates with closed circuit current and that therefore the winding of the receiving magnet 215 is normally energized over the conductors *a* and *b*. This may be accomplished, for instance, by a remote switching-in operation through the subscriber's loop, by means of which both the driving motor of the apparatus and at the same time 20 the compressor for the production of the compressed air and suction air are also put into operation. Such devices and expedients are conventional in this particular art, and their illustration is therefore omitted. In this manner the 25 armature 216 is normally held attracted by the magnet 215. In the normal position of rest shown super-atmospheric pressure is supplied to the coupling cylinder 223 through the conduit 224, by way of supply conduit 213, bore 211 of slide 30 valve 214, conduit 225, distributor 210, and the conduit 224 so that a drive coupling (not shown) of the telegraph device connected to the piston 226 of cylinder 223—and by which coupling the distributor shaft is operated—is released so that 35 this shaft stops rotating. Sub-atmospheric pressure is supplied at that time to the cylinder 227, in which moves the slide valve 214, by the control distributor 222 through the conduit 220, the cylinder 227 being not supplied at that time with 40 super-atmospheric pressure owing to the prevailing position of the control distributor 221.

The sub-atmospheric pressure prevailing in the cylinder 227 is, however, not sufficient to cause the piston 214 to move to the left against the 45 action of the magnet 215. Only upon the reception of the starting impulse—which in the case of closed circuit current operation is a "no-current" impulse—the magnet 215 is deenergized and the armature 216 and piston 214 are allowed 50 to move to the left. In this manner the conduit 212 communicates with the conduit 225 through the port 211 of the piston 214 so that a sub-atmospheric pressure is supplied to the cylinder 223 through the distributor 210 and the conduit 55 224, whereby the assumed coupling between the distributor shaft and the power channel is closed by the piston 226, whereupon the three distributors 210, 221 and 222 mounted on the common shaft begin to rotate. The ports of the several 60 distributors are so displaced with respect to one another that the port 228 first communicates with the conduit 219 and the cylinder 227 would be supplied with super-atmospheric pressure if this conduit were not closed by the piston 214. 65 Upon further rotation of the shaft, super-atmospheric pressure is supplied to the conduit 218 through the port 228 of the control distributor 221, so that the piston 214 turns to the right to its 70 position of rest and the armature 216 engages again the magnet 215. The different effect of the supply of the compressed air through the conduits 218 and 219 is attained by the fact that the conduit 218 is connected to the end wall and the conduit 219 to the cylindrical wall of the 75

cylinder 227. The distributor 210 has also been in the meantime moved out of its position of rest shown so that the conduit 224 and, therefore, the cylinder 223 are closed and continue to maintain a sub-atmospheric pressure and the coupling is maintained in the operating position. Upon the further rotation of the distributors the port 229 of the control distributor 222 communicates with the cylinder 227 through the conduit 220. The cylinder 227 is supplied in the position of rest with sub-atmospheric pressure and tends to move the piston 214 away from the magnet 215. If the magnet is reenergized in the meantime the piston remains in the right-hand, normal position, since the force of the magnet is greater than the force of the sub-atmospheric pressure. If the following impulse during the starting is a "current" impulse, the control slide valve 214 remains, therefore, in the position of rest, whereas upon the reception of a "no-current" impulse the sub-atmospheric pressure prevailing in the cylinder 227 causes the piston 214 to return to the left-hand end position, whereby the piston 214 closes the conduit 219 through which super-atmospheric pressure is supplied immediately following through the port 230 of the distributor 221. The super-atmospheric pressure is, consequently, no longer effective. Shortly thereafter the port 230 is brought into communication with the conduit 218 so that super-atmospheric pressure is supplied to the cylinder 227, thereby causing the piston 214 to return to its position of rest. The time which elapses between the connection of port 229 of the sub-atmospheric pressure control distributor 222 with the end of the cylinder 227 through the conduit 220 and the connection of the port 230 of the super-atmospheric pressure control distributor 221 with the side wall of the cylinder 227 through the conduit 219 is the time during which the mid-point scanning of the impulse is effected. By suitably varying the timing of the ports of one distributor relatively to that of the other distributors the moment and the duration of the scanning may be determined. By suitably mounting the control distributors on the shaft the displacement of the individual ports may be made adjustable and, therefore, the telegraph apparatus may be adapted to the distortion of the incoming telegraph impulses. The operation upon the energization of the magnet 215 by a "current" impulse corresponds to the operation in the case of the reception of "no-current" impulse. The cylinder 227 is supplied with super-atmospheric pressure through port 230 and conduit 219, immediately after the action of the sub-atmospheric pressure which acted through the port 229 of the distributor 222 and the conduit 220, i. e., immediately after the mid-point scanning, so that an interruption of the magnet current which now takes place can no longer cause a release of the armature.

After the reception of an impulse the piston 214, depending upon the kind of the impulse, is therefore in one of its end positions. Sub- or super-atmospheric pressure is supplied, therefore, to the distributor 210 through the conduit 225. At the next moment the distributor 210 comes into communication with the port 205 thus bringing the first piston of the cylinder 201 into a corresponding position. As soon as the operating distributor 210 has closed again the conduit 205, super-atmospheric pressure is again supplied to the conduit 218 and, therefore, to the cylinder 227 through the port 230 of the control distrib-

utor 221, so that the piston 214 to the right and is held there in position and the armature 216 engages again the magnet 215. This process repeats itself upon rotation of the distributors for all impulses of a telegraph signal combination so that after a complete rotation all pistons of the operating cylinder 201 are adjusted. As already above mentioned, instead of one common operating cylinder for the rack bar operating pistons also five individual cylinders may be provided which actuate selector bars. In this case the selector bars are adjusted after the distributor has made a complete rotation and the printing of the signal may begin. The coupling is disengaged at the moment at which the only port of the distributor 210 reaches the ports for the conduit 224 so that super-atmospheric pressure is again supplied to the cylinder 226, since the distributor 210, owing to the blocking current impulse, communicates with the pressure conduit 213. The printing of the signal may be effected in a known manner by a further piston which is also controlled by the operating distributor 210.

While in Fig. 7 the control member is designed in the form of a piston valve 214, Fig. 8 shows an arrangement in which a pop valve control is employed. For the sake of simplicity the revolving distributors are omitted in this figure, since they correspond substantially to those shown in Fig. 7.

In Fig. 8 the chamber 231 communicates continuously with the sub-atmospheric pressure side of the sub-atmospheric pressure generator through the conduit 232, whereas the conduit 233 in the state of rest is kept open by the revolving distributors so that atmospheric pressure prevails therein. At the other end of the valve spindle 234 is mounted a piston 235 which at the same time is designed as an armature for the receiving magnet 236. This piston 235 may be moved towards the magnet 236 by a compressed air impulse through the conduit 237. The supply of air to the operating distributor (corresponding to 210 in Fig. 7) is controlled by the two valve discs 238 and 239 mounted on spindle 234. Compressed air and suction air is supplied respectively to the chambers 240 and 241 through the conduits 242 and 243 by the pressure generator as indicated by the signs + and -. Depending upon the position of the valve stem either the chamber 240 or 241 communicates with the central chamber 244 so that the conduit 245 corresponding to the conduit 225 in Fig. 7 and extending to the operating distributor is supplied with either super- or sub-atmospheric pressure.

At rest the valve is in the position shown. Upon the arrival of the starting impulse the magnet 236 releases the armature 235 so that the valve stem 234 together with the armature 235 moves to the right under the influence of the pressure prevailing in the chamber 240, this movement being supported, if desired, by a spring 246. Compressed air is thus supplied to the conduit 245, thereby releasing as is described with reference to Fig. 7 the assumed distributor shaft coupling. The distributors start and the control distributors first close the supply conduit 233 and set up momentarily a pressure in the conduit 237, whereby the valve moves to the left. As soon as the valve disc 247 engages the cylinder it is firmly held in position by the sub-atmospheric pressure through the conduit 232. The distributors are relatively timed in such a manner that in the interval corresponding to the mid-point of the first telegraph impulse, the conduit 233 is mo-

- mentarily opened or is supplied with super-atmospheric pressure so that the valve disc 247 no longer adheres to the cylinder body. If, therefore, at this moment the magnet 236 is not energized the valve moves to the right and remains temporarily in this position. In the meantime the working distributor has caused the adjustment of the selector elements, for instance, of the first operating piston of the cylinder 201, Fig. 7. Shortly thereafter the conduit 245 is closed by the working distributor and the conduit 237 receives a compressed air impulse through the compressed air distributor so that the valve returns to the position of rest and is ready to receive the next telegraph impulse. This adjustment of the valve is repeated for each telegraph impulse and after the adjustment of the five selector elements the printing and the locking of the coupling is effected as described by reference to Fig. 7.

The invention is not limited to the embodiments shown. For instance, it is possible to use only one piston instead of a great number of pistons, in which case the individual impulses may be added or subtracted in the cylinder chamber depending upon the corresponding quantity of air. It is also not necessary to employ a rotary distributor, but a slide valve control may, for instance, be also used. Finally, it is immaterial in which sequence the pistons operate when employing a plurality of pistons such as in Fig. 1. It is preferable to operate first the piston having the longest stroke in order that its adjustment is properly completed at the end of the impulse combination in question.

The individual impulses may be allotted to the respective rotary and/or slide pistons in any desired manner. For instance, two piston systems may be provided which then control different movements of the part to be adjusted. A particularly advantageous form of the invention is obtained if at least the first and the last impulse is utilized by the same piston system, since in this case the advantage is obtained that an overlapping of the operating periods of the control members to be adjusted by the individual impulses is possible within the impulse combination.

For certain telegraph codes it is also possible to cause the individual pistons to operate, for instance, in the manner that individual pistons effect the shift of a group of characters (letter, number-shift, shift between two groups of letters), whereas the other pistons select the characters within the type group.

I claim as my invention:

  1. In a selector mechanism for translating electrically transmitted impulse combinations, means for receiving an electric impulse combination, positive and negative fluid pressure supply means controlled by said receiving means to supply positive or negative fluid pressure in accordance with the character of the received signal impulse, a selector responsive to said fluid pressures and a recording device coupled to said selector, so that the latter moves the recording character of said device corresponding to a given received signal combination into recording position, and a distributor connected between said fluid supply means and said selector for supplying successively fluid pressure impulses to said selector, and means connected with said receiver and controlled by the several electric impulse units of a received signal combination for controlling the operation of said distributor to admit to said selector a succession of fluid pressure impulses of a direction and character corresponding to the character of the received signal combination.

- source of positive and negative fluid pressure, and a distributor controlled by the arriving signal combination for admitting successively the desired kind of pressure impulse between each of 5 said pistons to move the latter in the desired direction, so that the sum total of the positive and negative piston movements represents the extent to which said recording device is moved to present the desired recording character.
- 10 5. In a selector mechanism for translating transmitted impulse combinations, a recording device movable to present the desired recording character in accordance with the transmitted impulse combination, a cylinder and a plurality 10 of pistons movably disposed therein and loosely coupled together so that each piston is movable relatively to the adjoining piston a given different number of path units, means for connecting the piston having the longest stroke to said 15 recording device so as to positively operate the latter, to present its different constituent characters, a source of positive and negative fluid pressure, and a distributor controlled by the arriving signal combination for admitting successively the desired kind of pressure impulse between each of 20 said pistons to move the latter in the desired direction, so that the sum total of the positive and negative piston movements represents the extent to which said recording device 25 is moved to present the desired recording character.
6. In a selector mechanism for translating transmitted impulse combinations, a recording device movable to present the desired recording character in accordance with the transmitted impulse combination, a cylinder and a plurality 30 of pistons movably disposed therein and loosely coupled together so that each piston is movable relatively to the adjoining piston a given different number of path units so that the strokes of the several pistons form a geometrical progression, means for connecting the piston having the longest stroke to said recording device so as to positively operate the latter, to present its different constituent characters, a source of positive and negative fluid pressure, and a distributor controlled by the arriving signal combination for admitting successively the desired kind of pressure impulse 35 between each of said pistons to move the latter in the desired direction, so that the sum total of the positive and negative piston movements represents the extent to which said recording device is moved to present the desired recording character.
- 40 7. In a selector mechanism for translating transmitted impulse combinations, a recording device movable to present the desired recording character in accordance with the transmitted impulse combination, a cylinder and a plurality 40 of pistons movably disposed therein and loosely coupled together so that each piston is movable relatively to the adjoining piston a given number of path units, a piston rod for positively connecting the piston having the longest stroke to said recording device to positively operate the latter, to present its different constituent characters, a source of positive and negative fluid pressure, and a distributor controlled by the arriving signal combination for admitting successively the desired kind of pressure impulse 45 between each of said pistons to move the latter in the desired direction, so that the sum total of the positive and negative piston movements represents the extent to which said recording device is moved to present the desired recording character.
- 50 8. In a selector mechanism for translating transmitted impulse combinations, a recording device movable to present the desired recording character in accordance with the transmitted impulse combination, a cylinder and a plurality 50 of pistons longitudinally slidably disposed therein and loosely coupled together so that each piston is movable relatively to the adjoining piston a given number of path units, a piston rod for positively connecting the piston having the longest stroke to said recording device to positively operate the latter, to present its different constituent characters, a source of positive and negative fluid pressure, and a distributor controlled by the arriving signal combination for admitting successively the desired kind of pressure impulse 55 between each of said pistons to move the latter in the desired direction, so that the sum total of the positive and negative piston movements represents the extent to which said recording device is moved to present the desired recording character.
- 55 9. In a selector mechanism for translating transmitted impulse combinations, a recording device movable to present the desired recording character in accordance with the transmitted impulse combination, a cylinder, a stationary central axle disposed therein, a radial vane fixed to the cylinder wall and extending therefrom closely to said axle and from end to end in said cylinder, and a plurality of rotary vane pistons extending from end to end in said cylinder and journalled to rotate on said axle and being loosely coupled together so that each piston is movable relatively to the adjoining piston and to said radial vane a given number of rotary path units, 60 means for positively connecting the piston having the longest stroke to said recording device to positively operate the latter, to present its different constituent characters, a source of positive and negative fluid pressure and a distributor 65
- 70 10. In a selector mechanism for translating transmitted impulse combinations, a recording device movable to present the desired recording character in accordance with the transmitted impulse combination, a cylinder, a stationary central axle disposed therein, a radial vane fixed to the cylinder wall and extending therefrom closely to said axle and from end to end in said cylinder, and a plurality of rotary vane pistons extending from end to end in said cylinder and journalled to rotate on said axle and being loosely coupled together so that each piston is movable relatively to the adjoining piston and to said radial vane a given number of rotary path units, 70 means for positively connecting the piston having the longest stroke to said recording device to positively operate the latter, to present its different constituent characters, a source of positive and negative fluid pressure and a distributor 75

controlled by the arriving signal combination for admitting successively the desired kind of pressure impulse between each of said pistons to move the latter in the desired direction, so that the sum total of the positive and negative piston movements represents the extent to which said recording device is moved to present the desired recording character.

11. In a selector mechanism for translating transmitted impulse combinations, a recording device movable to present the desired recording character in accordance with the transmitted impulse combination, a cylinder, a stationary central axle disposed therein, a radial vane fixed to the cylinder wall and extending therefrom closely to said axle and from end to end in said cylinder, and a plurality of rotary vane pistons extending from end to end in said cylinder and journalled to rotate on said axle and being loosely coupled together so that each piston is movable relatively to the adjoining piston and to said radial vane a given number of rotary path units, means for positively connecting the piston having the longest stroke to said recording device to positively operate the latter, to present its different constituent characters, a source of positive and negative fluid pressure and a distributor controlled by the arriving signal combination for admitting successively the desired kind of pressure impulse between each of said pistons to move the latter in the desired direction, so that the sum total of the positive and negative piston movements represents the extent to which said recording device is moved to present the desired recording character, and bores in said axle and said vane pistons for supplying the positive and negative fluid pressure between said pistons.

12. In a selector mechanism for translating transmitted impulse combinations, a character drum having a plurality of peripheral groups of signal characters and disposed to rotate and slide in axial direction to present the desired character to a given recording point, a cylinder and a plurality of pistons longitudinally slidingly disposed therein and loosely coupled together so that each piston is movable relatively to the adjoining piston and to the cylinder end a given number of path units, a piston rod for positively connecting the piston having the longest stroke to said character drum to positively shift the latter to bring its peripheral character group containing the desired character into registry with the recording point in accordance with a given portion of the transmitted signal impulse combination, a second cylinder axially aligned with said first cylinder, a stationary central axle disposed in said second cylinder, a radial vane fixed to the cylinder wall and extending therefrom closely to said axle and from end to end in said cylinder, and a plurality of rotary vane pistons extending from end to end in said cylinder and journalled to rotate on said axle and being loosely coupled together so that each vane is movable relatively to the adjoining vane and to said fixed radial vane a given number of rotary path units, means for slidably coupling the vane having the longest stroke to said character drum to positively rotate the latter to bring the desired character of the peripheral group selected by the pistons in the first cylinder into registry with the recording point in accordance with the remaining portion of the transmitted impulse combination, a source of positive and negative fluid pressure and a distributor for each of said cylinders controlled by the arriving impulse combination for admit-

ting to each cylinder successively the desired kind of pressure impulse between each of said pistons to move the latter in the desired direction, so that the total sum of the positive and negative piston movements in both cylinders represents the extent to which said drum is moved to present the desired character to the recording point in accordance with the total signal impulse combination.

13. In a selector mechanism for translating transmitted electric impulse combinations, having an electric impulse receiver, a source of positive and negative fluid pressure supply, a selector responsive to positive and negative fluid pressure impulses, and a recording device coupled to said selector, so that the latter moves said device in accordance with the selector response to said pressure impulses to present the desired recording character to a given recording point in accordance with the received electric impulse combination, a plurality of fluid pressure distributors disposed to control the fluid supply to said selector, and a control element responsive to a received electric impulse for controlling the operation of said distributors in accordance with the received electric impulse combination, for supplying in accordance with the relative distributor port positions fluid pressure impulses to said selector only during the mid-time period of duration of each electric impulse of the received impulse combination.

14. In a selector mechanism for translating transmitted electric impulse combinations, having an electric impulse receiver, a source of positive and negative fluid pressure supply, a selector responsive to positive and negative fluid pressure impulses, and a recording device coupled to said selector, so that the latter moves said device in accordance with the selector response to said pressure impulses to present the desired recording character to a given recording point in accordance with the received electric impulse combination, a plurality of fluid pressure distributors disposed to control the fluid supply to said selector, and a control element responsive to a received electric impulse and actuated by the varying positive and negative fluid pressure effects produced by said distributors, for controlling said distributors in accordance with the received electric impulse combination, for supplying in accordance with the relative distributor port positions fluid pressure impulses to said selector only during the mid-time period of duration of each electric impulse of the received impulse combination.

15. In a selector mechanism for translating transmitted electric impulse combinations, having an electric impulse receiver, a source of positive and negative fluid pressure supply, a selector responsive to positive and negative fluid pressure impulses, and a recording device coupled to said selector, so that the latter moves said device in accordance with the selector response to said pressure impulses to present the desired recording character to a given recording point in accordance with the received electric impulse combination, a plurality of fluid pressure distributors disposed to control the fluid supply to said selector, and a control element responsive to a received electric impulse and actuated by the varying positive and negative fluid pressure effects produced by said distributors, for controlling said distributors in accordance with the received electric impulse combination, for supplying in accordance with the relative distributor port posi-

tions fluid pressure impulses to said selector only during the mid-time period of duration of each electric impulse of the received impulse combination, and port connections between said distributors and said control element for returning said element by fluid pressure impulses into its normal position after each electric signal impulse is received.

16. In a selector mechanism for translating transmitted electric impulse combinations, having an electric impulse receiver, a source of positive and negative fluid pressure supply, a selector responsive to positive and negative fluid pressure impulses, and a recording device coupled to said selector, so that the latter moves said device in accordance with the selector response to said pressure impulses to present the desired recording character to a given recording point in accordance with the received electric impulse combination, a working fluid pressure distributor disposed to control the fluid supply to said selector, a fluid pressure control valve for said distributor controlled by said electric receiver and arranged to assume two operating positions to supply either positive or negative fluid pressure to said working distributor, depending upon the operating condition of said receiver, two control distributors disposed to operate synchronously with said working distributor, one control distributor being directly connected with the positive and the other with the negative fluid pressure supply, and fluid conduit connections between said control distributors and said control valve for actuating said valve to assume the one or the other of its two operating positions in accordance with the prevailing fluid pressure supply positions of said control distributors and subject to the operating condition of said receiver.

17. In a selector mechanism according to claim 16, a fluid pressure control valve comprising a cylinder and a sliding piston disposed therein and connected to the electric receiver, the end of said cylinder being connected to either of the two control distributors so as to have positive or negative fluid pressure supplied to it, and the peripheral cylinder wall portion along the piston

stroke being connected with the positive fluid pressure control distributor whereby according to the positions of said distributors and the condition of said receiver said piston may be moved into one or the other of its two operating positions to supply the desired kind of fluid pressure to the working distributor at the desired time moment. 5

18. In a selector mechanism according to claim 16, a pair of control distributors mounted on a common shaft with the working distributor and being circumferentially adjustable relatively to one another and to the working distributor for adjusting the timing of the fluid pressure supply with respect to the occurrence of respective electric impulses. 10 15

19. In a selector mechanism according to claim 16, a fluid pressure control valve comprising a cylinder having two end chambers connected respectively to the positive and a negative pressure control distributor, a central delivery chamber connected to the working distributor and a supply chamber on either side of said central chamber, a valve rod passing through all of said chambers, said supply chambers being respectively connected with the positive and the negative fluid pressure supply and having ports connecting them with said delivery chamber, and valves in said delivery chamber fixed on said valve rod for controlling said ports so that when one port is open the other is closed, a piston in the positive end chamber fixed on said valve rod and connected with the operating element of the electric impulse receiver, and a valve disc mounted on said rod and disposed to cover the other negative end chamber, and a spring tending to move said disc to open said chamber and to move the operating element of the receiver away from the latter and to supply positive fluid pressure to said working distributor, when the negative control distributor has permitted the negative pressure to sufficiently decrease after the reception of a signal impulse, so that the delivery chamber is supplied with the desired fluid pressure only during the mid-time period of the duration of a signal impulse. 40 45 30 35
